FIG. 1

FIG. 2

FIG. 3

FIG. 4

FIG. 5

FIG. 6

FIG. 1 is a top and side perspective view of a pet house, showing one form of our new design;

FIG. 2 is a bottom and opposite side of the form shown in FIG. 1;

FIG. 3 is a fragmentary top and side perspective view of the form shown in FIG. 1 with the reversible top inverted;

FIG. 4 is a top and side perspective view of a pet house, showing another form of our new design;

FIG. 5 is a bottom and opposite side perspective view of the form shown in FIG. 4; and

FIG. 6 is a fragmentary top and side perspective view of the form shown in FIG. 4 with the reversible top inverted.

The exterior and interior surfaces of the sides, the interior surface of the bottom, and one side of the reversible top have been stippled to indicate contrast in appearance.

We claim:

The ornamental design for a pet house, substantially as shown and described.
